(57) **CLAIM**

I claim the ornamental design for an electrical connector, as shown and described.

DESCRIPTION

FIG. 1 is a top plan view of an electrical connector, showing my new design;

FIG. 2 is a front elevational view thereof;

FIG. 3 is a bottom view thereof;

FIG. 4 is a right side elevational view thereof;

FIG. 5 is a left side elevational view thereof;

(Continued)

FIG. 6 is an enlarged left perspective view thereof; and, FIG. 7 is an enlarged right perspective view thereof. The broken line portion of the figure drawings is included to show environmental structure that forms no part of the claimed design.

1 Claim, 7 Drawing Sheets
